ABSTRACT: Methods are disclosed for making cylindrical cup electrodes for three-gun color picture tubes having internally mounted shield inserts of magnetic material affixed to the inner walls of the cup. The upper rim of the cup is kept intact and may be flanged outwards to improve roundness after apertures are formed in the cup sidewalls. Apertures in the cup walls are confined to those required for magnetic pole pieces extending into said cup comprising three pairs of slits in the sidewalls of the cup.

METHODS OF MAKING CONVERGENCE CUP ELECTRODES BY AFFIXING SHIELDS TO INNER CYLINDER WALLS

This application is a division of the copending application Ser. No. 788,777 filed Jan. 3, 1969, now U.S. Pat. No. 3,513,479 issued May 19, 1970 which, in turn, is a continuation-in-part of application Ser. No. 633,822, filed Apr. 26, 1967, now U.S. Pat. No. 3,441,769 issued on Apr. 29, 1969.

This invention relates to methods of making electrodes for controlling a beam within a cathode-ray tube, and more particularly, it relates to a convergence cup electrode for three beam color television tubes.

Basically, this convergence cup electrode is a cuplike electrode of generally cylindrical shape of a thin-walled nonmagnetic metal. Inside the cup is a generally Y-shaped magnetic shield dividing the interior of the cylinder into three substantially equal compartments. A set of two magnetic pole pieces protrude from the outside through two slots in each compartment to straddle an aperture in the closed cup bottom which passes an electron beam. Snubber springs are affixed to extend generally outwardly from the electrode to press against the inside surface of the glass neck of the cathode-ray tube for centering the gun therein. The pole pieces have flanges adjacent the outer walls of the electrode and near the glass neck of the tube to communicate with convergence magnets located outside the tube envelope.

In constructing this convergence cup assembly, great difficulty has been encountered in holding the roundness of the convergence cup cylinder. It has been found that in punching six pole piece slots and three shield slots through the electrode walls, the cylindrical shape may be distorted out of tolerance.

It has been customary to nick or slot the top edge of a convergence cylinder at three positions about the periphery in order to extend a flange on the Y-shaped shields through the cylinder walls for welding onto the outer cylinder surface. This procedure has long been customary in commercial practice despite the many problems it produces. The cost and maintenance of dies that are needed to punch through stainless steel convergence cup walls is significant. The punching technique is complicated seriously by the roundness of the walls that tends to deflect dies and make precise positioning of slots difficult, to say nothing of excessive die wear.

Furthermore, roundness acceptance tolerances of a convergence cup are strict, and any punching or slotting, particularly at the rim edge of a cup tends to misshape the cup and cause out of roundness. Also punched slots provide surfaces which may develop burrs or sharp edges subject to corona discharge and defective operation in the high-voltage environment of cathode-ray tube electrodes. Such slots are usually inaccessible to effective tumbling and deburring operations even if the cost of this additional step can be borne.

In spite of all these deficiencies, cathode-ray tube color picture gun assemblies have for the past decade consistently mounted the V-shaped convergence shields by extending flanges through a slot in the cylinder walls so that they could be welded on the outside of the cup. Perhaps in this critical art subject to defect when a minor change is made that will tend to disturb the electron beam characteristics or voltage distribution, there has been a reluctance to put a welded surface inside the electrode cup.

It is therefore an object of this invention to provide methods of making a convergence cup electrode structure resolving these deficiencies of the prior art.

Another object of the invention is to provide methods of making convergence cup electrode assemblies while holding precise roundness tolerance during manufacture.

It has been discovered in accordance with this invention that the convergence cup may be made more precisely at less cost with structure successfully operating in the critical environment of a color picture tube gun exposed to high voltage for shaping, controlling and directing an electron beam with

precision over a large range of conditions. Thus, the punched slots in the convergence cup at the rim edge are avoided to thereby provide better roundness of the convergence cup and to avoid problems caused by burrs and other distortions of the electric field configuration affecting the electron beam. Accordingly the V-shaped shield members are affixed to the inner walls of the convergence cup cylinder with flanges abutting the walls near the rim at the open end of the cup. The abutted flanges are mounted in a position shielded from the electron beam by the magnetic convergence pole pieces to prevent any danger of distorting the beam with distorted inner cup wall surfaces caused by the welding or flange structure.

These and other aspects and objectives of the invention are related throughout the following detailed description which refers to the single FIGURE in the accompanying drawing, which shows a top view of a convergence cup assembly.

As seen from the drawing, the convergence cup may be a deep-drawn cylinder having a closed bottom 10. This cup has thin sidewalls of nonmagnetic metal such as stainless steel and may have the upper rim 14 flange outwardly. Slots 15, 16 extend through the cup walls defining the limits of three separate compartments 18, 19, 20 through which an electron beam is passed.

Two magnetic pole pieces 30, 31 extend through slots 15, 16 into each compartment 18, 19, 20 to straddle apertures 32, 33, 34 which permit the three separate electron beams of a color picture tube to pass through the convergence cup electrode. The flanges 8 on the pole pieces 30, 31 abut the outer walls of the cylinder to extend near the inner wall of the glass neck of the tube 35 about which a conventional convergence magnet array (not shown) is placed to communicate with the pole pieces 30, 31 at each compartment.

Three V-shaped magnetic shield members 23, 24, and 25 extend radially from their common apex at the center 26 of the cup to the cylinder walls forming three substantially equal compartments in the cup to further isolate the three beam compartments within the convergence cup assembly. These shields 23, 24, 25 are wholly contained within the cup and extend substantially to the bottom of the cup. They are spot-welded to the inner sidewalls of the cylinder near the upper rim 14 by means of flanges 21, 22 bent from the plane of each shield to extend circumferentially adjacent the inner surface of the cylinder toward the magnetic pole pieces 30, 31. Any possible weld spots or disturbed magnetic or electric field patterns left inside the convergence cup by this mounting structure are shielded from the beam, which passes through the apertures 32, 33 and 34, by means of the intervening pole pieces 30, 31.

Thus it has been found in practice that this convergence cup construction provided by this invention affords improved cathode ray picture tube performance, yet is less expensive to manufacture than former structure, thereby leading to widespread commercial use.

I claim:

1. The method of forming a convergence cup electrode for a three beam color tube comprising the steps of
  - a. forming a cylinder of nonmagnetic metal with thin walls having a continuous open upper rim,
  - b. forming in the walls of said cylinder, at a position intermediate the upper and lower rims, apertures located in positions for receiving therethrough to extend within the cylinder three pairs of magnetic convergence pole pieces straddling the path of each of said beams through said cylinder, while retaining the continuous upper rim intact and without substantially changing the roundness of said cylinder, and
  - c. welding flange portions of magnetic convergence pole pieces to the cylinder exterior such that said pole pieces extend through the apertures into the cylinder, and
  - d. forming a set of magnetic shields to fit wholly within said cylinder with flanges extending therefrom to fit circumferentially adjacent the inner cylinder walls, and

- e. welding said flanges to said cylinder to affix to the inner walls of said cylinder to extend wholly within said cylinder, said set of magnetic shields forming therewith three separate compartments respectively containing the pairs of said pole pieces. 5
- 2. The method defined in claim 1 including the step of flanging the upper rim of said cylinder outwardly before forming said apertures in said cylinder.
- 3. The method defined in claim 1 including the step of forming the flanged shield means of three V-shaped members. 10
- 4. The method of making a convergence cup electrode assembly for positioning in the neck portion of a three beam color television cathode ray tube comprising the steps of
  - a. forming a hollow cylindrical thin walled cup with a closed bottom and open top with an upper rim thereabout forming an electrode body of nonmagnetic material with three apertures defined in the closed bottom to pass said three beams and with a solid unapertured upper rim, said 15

20

cylinder having only one set of three pairs of slots provided in the cylinder walls receiving and positioning magnetic convergence pole pieces on either side of each of said apertures in the bottom to permit the three beams to pass through the cup in a substantially axial path, between said pole pairs,

- b. forming flanged shield means of magnetic material for fitting wholly within the cup to extend radially from a flange formed to conform adjacent the cylinder walls to the center of the cylinder to form three compartments encompassing the respective beam paths with the surrounding pair of convergence pole pieces, and
- c. affixing the shield means only to the inner walls of said cylinder by welding the flanges on the shield means to the inner walls at positions located between the pairs of pole pieces.
